AMUSEMENT APPARATUS

Arthur W. Swenson, Rockford, Ill.

Application March 30, 1936, Serial No. 71,660

7 Claims. (Cl. 273—121)

This invention relates to amusement apparatus of the type in which balls are projected onto an inclined playing surface within a closed casing and allowed to gravitate therealong into different scoring pockets.

One object of the invention is to provide an amusement apparatus of the above character having a novel device for enabling a player to intercept or catch a ball rolling down along the playing surface and to control the projection of such ball upwardly along the surface toward a selected target or scoring pocket.

Another object is to associate with the ball receiving device a power operated kicker or shooter arranged to project a caught ball at any angle selected by the player.

A further object is to provide a ball catching device arranged in the above manner and adapted to be positioned selectively for catching balls and directing the angle of projection thereof by means operable manually from a point exteriorly of the casing in which the playing surface is housed.

The invention also resides in the novel construction of the movable ball receiving device which enables balls to be caught readily and yet guided accurately in their projection from the device and which delays the projection of a ball after the latter has been caught so as to afford a time interval during which the player may adjust the position of the device for shooting the ball in the desired direction.

Still another object is to provide amusement apparatus of the above general character having a score register responsive to balls received in different pockets, and means operating at random and independently of the will of the player to vary the score recorded on the register by different balls received in the same pocket.

Other objects and advantages of the invention will become apparent from the following detailed description taken in connection with the accompanying drawings, in which

Figure 1 is a plan view of an apparatus embodying the novel features of the present invention.

Fig. 2 is a section taken along the line 2—2 of Fig. 1.

Fig. 3 is a section taken along the line 3—3 of Fig. 2.

Fig. 4 is a section taken along the line 4—4 of Fig. 6.

Figs. 5 and 6 are sections taken along the lines 5—5 and 6—6 of Fig. 4.

Fig. 7 is a section taken along the line 7—7 of Fig. 1.

Fig. 8 is a fragmentary perspective view of a modified form of ball catching and projecting device.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the exemplary form shown in the drawings, the invention is embodied in apparatus of the so-called bagatelle type comprising a box-like casing 10 having a transparent top or cover 11 and supporting a flat plate or board 12 providing an upper playing surface 13 which is inclined at an angle such that balls 14, which are used in the play, will gravitate readily therealong. By manipulation of a ball lift operating member 15 and a plunger or shooter 16 in a well known manner, balls stored within the casing 10 may be projected along a guideway 17 onto the upper portion of the playing surface.

The balls gravitating along the surface may be received in irregularly spaced pockets formed by holes 18 and pins 19 upstanding therearound. A ball falling through any one of the holes is received in an inclined channel 20 mounted on the underside of the board 12 and arranged to direct the ball back to the storage reservoir. The balls passing all of the holes roll into a channel 21 and are returned to storage through a hole 22.

The invention contemplates the provision of a shiftable pocket or catching device generally indicated by the numeral 23 and controllable from a point exteriorly of the casing 10 to enable the player to catch a ball rolling down along laterally spaced portions of the playing surface and to control the upward projection of the ball toward a selected target or high scoring pocket. In the present instance, the device 23 comprises an elongated U-shaped channel opening upwardly along the playing surface and having side walls 25 rigid with and upstanding from a plate 26 clamped by screws 26^a to an upright sleeve 27 which projects through an aperture in the lower part of the board 12 and is journaled in a bearing 28. The pocket is thus supported from its lower end to swing horizontally across the playing surface so that its upper open end may be positioned to receive balls rolling down different portions of the playing surface.

Preferably, swinging of the pocket from side to side is effected by manually shifting a handle 30 on the outer end of a rod 31 projecting through and slideable endwise in the front wall of the casing 10. The other end of the rod is upturned and connected to the free end of an arm 32 rigid with and projecting laterally from a plate 33 clamped by the screws 26^a to the lower end of the sleeve 27. The pocket 23 will be swung counter-clockwise 10 when the knob 30 is pushed inwardly and clockwise by pulling outwardly on the knob.

The pocket is equipped with a power actuated kicker for projecting a caught ball upwardly out of the pocket in a direction determined by the angular setting of the pocket. Herein the kicker comprises a stiff arm 34 and a parallel flexible arm 35 separated by blocks 36 of insulation and clamped by screws 37 to a plate 38 which is pivoted on a horizontal pin 39 supported in bracket arms 40 depending from the plate 33. The free ends of the kicker arms extend upwardly through the sleeve 27 and close the lower end of the pocket 23 so as to be engaged by a ball rolling into the pocket.

A leaf spring 41 fast on the plate 38 and bearing at its free end against the core 42 of a magnet 43 normally maintains the arms 34 and 35 retracted as shown in Fig. 2. The magnet is supported by a bracket member 44 on the plate 33. When the coil of the magnet is energized, the plate 38, which constitutes the magnet armature, will be attracted, and the upper ends of the arms 34 and 35 will be projected longitudinally of the pocket toward the upper end thereof. Accordingly, a ball in the pocket will be projected upwardly along the playing surface 13.

Preferably provision is made for energizing the magnet 43 automatically as an incident to movement of a ball into the lowermost portion of the pocket. This is accomplished by controlling the energizing circuit (not shown) of the magnet by a switch 45 comprising contacts carried by the arms 34 and 35 and arranged to engage each other and close the switch when the arm 35 is engaged and flexed by a ball rolling into the pocket. To allow the player sufficient time after catching the ball to set the pocket 23 for upward projection of the ball at the desired angle, the side walls 25 of the pocket are made relatively long so that the desired time interval elapses between entry of the ball in the upper end of the pocket and engagement of the ball with the arm 35.

The sides 25 of the pocket are spaced apart a distance only slightly greater than the diameter 55 of the balls 14 so that the walls act as guides in directing the course of the projected ball. At their upper ends, the walls 25 are flared outwardly and are curved as indicated at 47 to form a cup-shaped opening for the pocket, which opening 60 has a width substantially greater than the diameter of the balls. With the pocket thus constructed, catching of a ball is facilitated since the open end of the pocket need be positioned only in the approximate line of gravitation of the ball along the playing surface. Thus a player 65 may, by quick movement of the handle 30, position the pocket to receive a downwardly rolling ball and then may, by quickly turning the pocket to the proper position, cause the ball to be projected in the desired direction.

The targets toward which the player tries to direct a ball projected from the pocket 23 may take various forms. Herein these pockets comprise holes 50 and 51 positioned near the top of 75 the playing surface and partially surrounded by

rows of pins 52 and 53 so as to prevent downwardly rolling balls from entering these holes. In the present instance, a ball may be projected from the pocket 23 directly into the area surrounding the hole 51, pins 54 being spaced around the lower side of the hole to permit a ball to pass between them and to facilitate deflection of the ball into the hole. A ball may be rolled into the hole 50 only by rebounding from one of several deflectors 55 comprising leaf springs anchored in fixed blocks 56 and set at the proper angles. A flexible deflector 57 also serves to direct balls rebounding from the springs 55 into the area surrounding the hole 50. Thus, when the pocket 23 is positioned as shown in dotted outline in Fig. 1, a ball projected therefrom will strike one of the springs 55 and will be deflected by the spring 57 toward the pins 52 from which it may rebound into the hole 50 or roll back down the playing surface.

In order to provide for a wider range of movement of the pocket 23, the latter may, if desired, be arranged for bodily movement laterally of the board 12 as well as for pivotal movement. For this purpose the sleeve 27 may be disposed in a horizontal slot 60, Fig. 8, extending transversely of the board and mounted on a block 61 slideable along a rod 62 which is mounted beneath the board. The block supports a flange 63 which projects through a slot 64 in the front wall of a casing 10 and slideably supports the rod 31. By shifting the knob 30 laterally, the entire pocket support may be moved, while the pocket may be swung about its pivot by moving the rod 31 endwise in the manner previously described.

If desired, projection of a ball caught in the pocket 23 may be controlled manually. To this end the switch 45 is connected in series with a switch operated by a push button 65 supported by the knob 30, Fig. 8.

Games of the character above described are frequently equipped with means for indicating the cumulative score made by rolling balls, into the different holes. Such indication may be given by numbers appearing through a window 70 in the board 12 and carried on the periphery of a disk 71 loose on a shaft 72 supported in the casing 10 beneath the board 12. Means is provided for advancing the indicator disk with a step-by-step movement. Herein this means includes a clock spring 73 coiled about the shaft 72 and having one end anchored at 74 in the disk and the other end fixed to a ratchet wheel 75 loose on the shaft and held against counter-clockwise rotation by a check pawl 76. The spring 55 is kept wound by reciprocation of a pawl 77 engaging the ratchet wheel and mounted on a rod 78 which is arranged to be reciprocated each time the ball lift 15 is actuated.

Normally the wheel 71 is held against rotation by a pawl 79 engaging gear teeth 80 on the wheel and carried by a bell crank lever 81 pivoted at 82.

Rotatably supported by a pin 83 on the lever 81 is a gear segment 84 urged by a spring 85 into the position shown in Fig. 7. As the lever 65 81 is swung to retract the pawl against the action of a spring 90, the teeth 86 of the segment are carried into mesh with the teeth 80 so that the segment rotates with the wheel 71 under the action of the spring 73 until a pin 87 on the segment engages a stop shoulder 88 on the lever 81. In this way, the disk is advanced through a predetermined angle each time the lever 81 is operated. Operation of the latter occurs upon each energization of an electromagnet 91 having 75

an armature 92 pivoted intermediate its ends at 93 and bearing upwardly at its outer end against a roller 94 on the lever 81.

The magnet 91 is arranged to be energized one or more times in response to the movement of each ball along the channels 20 after falling through one of the holes 18, 50, and 51. This is accomplished by depression of fingers 95 to 98 pivoted at 99* on the underside of the board 12 and extending upwardly into the channels 20 through slots 99 in the bottoms thereof. Leaf springs 100 anchored at 101 urge the fingers upwardly into the position shown in Fig. 4. The spring 100 cooperates with the contact on a second leaf spring 102 to form a switch 103 which is normally open but is closed by depression of the finger by a ball rolling down the channel. The finger 95 is positioned centrally of the channel so as to be engaged by each ball.

Preferably, the other fingers 96, 97, and 98 are spaced longitudinally of the channel 20 leading from the high scoring pockets 50 and 51 and are positioned laterally of the channel so that a ball may roll past each finger without engaging the same depending on the path which the ball takes. For this purpose the channel is made substantially wider than the ball and the fingers are located so that the distances between them and opposite side walls are respectively greater and less than the ball diameter.

It will be thus seen that if a ball falling through the hole 50 takes the proper path, all of the fingers 95 to 98 will be depressed causing the magnet to be energized four times and the counter-wheel to be advanced four steps. Or the ball may pass the fingers 96, 97, and 98 in which case the wheel would be advanced one step only in response to depression of the finger 95. If the fingers 95 and 96 alone are engaged, the wheel will be advanced two steps. From the foregoing it will be seen that the score registered by advance of the wheel 71 in response to the ball falling through one of the holes 50 or 51 will be varied at random and independently of the will of the player. Such action adds materially to the interest of playing the game.

I claim as my invention:

1. Amusement apparatus having, in combination, an inclined playing surface down which balls may gravitate, a pocket for catching balls disposed above said surface including elongated parallel walls spaced apart a distance somewhat greater than the diameter of one of said balls so as to constitute a ball guideway and extensions of said walls diverging from the walls to define a substantially widened open end for said pocket, means supporting said pocket with said open end facing upwardly along said surface and for movement of the end laterally of the surface into different positions for catching balls gravitating along different positions of the surface, manually controllable means by which said pocket may be shifted to different selected positions, a kicker movable with said pocket and adapted when actuated to project a caught ball upwardly out of the pocket along said surface and between said walls, and means positioned for engagement with a caught ball rolling to the lower portion of said guideway to effect automatic actuation of said kicker.

2. Amusement apparatus having, in combination, an inclined playing surface down which balls may gravitate, a pocket for catching balls disposed above said surface and having an open end facing upwardly along the latter, said open

end being substantially wider than the diameter of said balls, means supporting said pocket for movement of said open end laterally of said surface to position the same for catching balls rolling down different portions of the surface, selectively operable means for positioning said pocket, a kicker movable with said pocket and adapted when actuated to project a caught ball out of said pocket upwardly along said surface in a direction determined by the position of the pocket, and means engageable with a ball rolling along said surface within said pocket to effect automatic actuation of said kicker.

3. Amusement apparatus having, in combination, an inclined playing surface down which balls may gravitate, a pocket for catching balls disposed above said surface and having an open end facing upwardly along the latter, said open end being substantially wider than the diameter of said balls, means supporting said pocket for movement of said open end laterally of said surface to position the same for catching balls rolling down different portions of the surface, selectively operable means for positioning said pocket, a kicker movable with said pocket and adapted when actuated to project a caught ball out of said pocket upwardly along said surface in a direction determined by the position of the pocket, and means engageable with a ball rolling along said surface within said pocket to effect automatic actuation of said kicker.

4. Amusement apparatus having, in combination, an inclined playing surface down which balls may gravitate, a pocket having side walls cooperating with said surface to define an elongated ball guideway with an enlarged open end, means pivotally supporting said pocket above said surface to turn about an upright axis adjacent the opposite end of said guideway whereby to permit the said enlarged end of the guideway to be shifted laterally of said surface for receiving balls gravitating along different portions of the surface, manually operable means by which said pocket may be swung about said axis to position said open end selectively, a power actuated kicker member disposed in said guideway adjacent said axis and adapted when actuated to move upwardly along said guideway irrespective of the angle at which said guideway may be disposed, and means operating in timed relation to movement of a caught ball along said guideway to cause automatic actuation of said member and reprojection of the ball thereby along said guideway.

5. Amusement apparatus having, in combination, an inclined playing surface down which balls may gravitate, an elongated pocket having an opening at one end facing upwardly along said surface, means pivotally supporting said pocket to turn about an upright axis spaced from said opening whereby to permit said opening to be positioned selectively across said surface for receiving balls rolling down different portions thereof, a power operated kicker member disposed in said pocket and adapted when actuated to move upwardly along said surface longitudinally of said pocket irrespective of the angular position of the latter, and means for causing automatic actuation of said member in response to movement of a caught ball to the lower portion of said pocket, the side walls of said pocket serv-

ing to guide the reprojected ball and determine the direction of discharge thereof from the pocket.

6. Amusement apparatus having, in combination, an inclined playing surface down which balls 5 may gravitate, a pocket for catching balls disposed above said surface and having an open end facing upwardly along the latter, said open end being substantially wider than the diameter of said balls, means supporting said pocket for movement 10 of said open end laterally of said surface, manually controllable means by which said pocket may be shifted selectively for catching balls rolling down different portions of said surface, a control member positioned for engagement 15 with a ball rolling down said surface within said pocket, and a kicker actuated automatically in response to engagement of said member by a caught ball and operable when so actuated to re-project the ball upwardly along said surface in a 20 direction predetermined by the position of the pocket at the time of such reprojection, said pocket including means for interposing a sufficient delay between entry of a ball in said open end and engagement of said member to permit of reposi-

tioning of said pocket for reprojection of the ball along any selected path.

7. Amusement apparatus having, in combination, an inclined playing surface down which balls 5 may gravitate, a pocket for catching balls disposed above said surface including elongated parallel walls spaced apart a distance somewhat greater than the diameter of one of said balls so as to constitute a ball guideway and extensions of said walls diverging from the walls to define a substantially widened open end for said pocket, means supporting said pocket with said open end facing upwardly along said surface and for movement of the end laterally of the surface into different positions for catching balls gravitating along 15 different positions of the surface, manually controllable means by which said pocket may be shifted to different selected positions, mechanism movable laterally of said surface with said pocket and adapted when actuated to project a caught 20 ball in the pocket upwardly along said surface at an angle determined by the position of said walls at the time of such projection.

ARTHUR W. SWENSON.
